UNITED STATES PATENT OFFICE.

MELVIN D. KILMER, OF CLEVELAND, OHIO.

WIRE-BENDING DEVICE.

1,261,550.

Specification of Letters Patent.

Patented Apr. 2, 1918.

Application filed January 2, 1917. Serial No. 140,065.

To all whom it may concern:

Be it known that I, MELVIN D. KILMER, a citizen of the United States, resident of Cleveland, county of Cuyahoga, and State 5 of Ohio, have invented new and useful Improvements in Wire-Bending Devices, of which the following is a specification, the principle of the invention being herein explained and the best mode in which I have 10 contemplated applying that principle, so as to distinguish it from other inventions.

My invention relates to devices for bending wire, its object being to provide a device of this character which will be simple and 15 economical in structure, efficient in operation and lend itself to the making of an unlimited number of accurate forms from wire and other material.

The annexed drawing and the following 20 description set forth in detail certain means embodying my invention, the disclosed means, however, constituting but one of various mechanical forms in which the principle of the invention may be employed.

25 In said annexed drawing:—

Figure 1 represents a front elevation of my new and improved wire bending device; Fig. 2 represents a central longitudinal section thereof taken in the plane indicated by 30 the line II—II, Fig. 1; Fig. 3 represents a partial front elevation of certain elements of said device when the crank portion thereof has been carried to its extreme operative position; Fig. 4 represents a partial front 35 elevation when said crank has been retracted and carried back to its other extreme position; and Figs. 5 and 6 represent details of an arbor and an oscillatory member hereinafter fully described.

40 My invention, as illustrated, consists of a main frame 1 preferably of cast iron. The lower portion of this frame is provided with a transverse shoulder 2 which in conjunction with a bolt (not shown) passing 45 through a hole 3, may securely fix the device to a bench or table, as will be readily understood.

The other end of the frame 1 is formed with a circular depression 4 intersected by 50 bore 5. Seated in this depression 4 is a cylindrical member 6 formed with a cylindrical hollow stem 7 disposed in the bore 5. The hollow stem 7 is fastened by means of screw 8 to a bushing 9 formed upon the inner end 55 of a crank-handle 10. Contained within the hollow stem 7 by means of a screw 11 is an

arbor 12 formed with a plurality of sections 13 of varying cross-sectional areas, by means of shoulders 14 whereby different sizes of eyes 23 may be formed. Projecting from 60 the face of the cylindrical member 6 and transversely adjustable relatively to the arbor 12 is a short hard steel pin 15. This transverse adjustment is secured by reason of said pin 15 being mounted in a plate 16 65 which is contained in a depression 17 in the cylindrical member 6, such pin 15 being further, vertically adjustable in the plate 16 and is held to the properly adjusted position by means of set screw 18 to which 70 said screw access is obtained by means of a countersunk portion 19 in the cylindrical member 6, as plainly seen in Fig. 1. A strap 20 is secured to the periphery of the member 6 and is intersected by a screw 21, 75 which works in the plate 16 to effect the transverse adjustment of the latter. The distance between the pin 15 and that section 13 of the arbor which happens to be in use, is made such as to allow the wire 22 to just 80 pass between section 13 and pin 15. The frame 1 is formed with two lugs 24 receiving screws 25, which provide adjustable stops limiting the oscillatory movement of a member 26, as will be hereinafter fully de- 85 scribed. This oscillatory member 26 comprises two relatively adjustable portions 27 and 28 intersected and joined by screws 29 by means of which such adjustment is obtained, a third screw 30 intersecting the portion 28 and being withdrawn from contact 90 with the member 7 when an adjustment is being made and being screwed up into tight contact with said member 27 when the proper adjustment has been secured. This 95 adjustment is for the purpose of providing a groove 31 of the proper size to receive the wire which is to be bent. The frame 1 is intersected by a longitudinal groove 32, Fig. 2, disposed centrally of the longitudinal axis 100 of the member 26, and by which said member 26 is oscillatorily secured to the frame 1 through the medium of bolt 33 and is further thereby made adjustable longitudinally of the frame. A lock nut 38 is also 105 provided, as shown.

The surface of that part of the frame 1 beyond the cylindrical member 6 is graduated, as shown, to indicate inches beyond the pins 15 and the arbor 12, and this surface is so located as to be in proximity to the wire 22 when the latter is in the holding 110

member 26, and extends beyond the end of the latter, as shown in dotted line in Fig. 1.

The device as thus far described operates as follows:

5 The wire to be bent is held in the groove 31 of the member 26, the crank-handle 10 moves so as to bring the pin 15 on the left-hand side of the arbor 12 and the wire then pushed through the groove 31 between said 10 pin 15 and said arbor 12 the desired distance beyond same as may be indicated by the gage formed by the graduated surface previously referred to. By then carrying the crank in the direction indicated by the 15 arrow, the wire may be bent as desired. In order to insure the proper amount of offset of the eye 23, the frame 1 is provided with a lug 34 containing a transverse groove 35 and an adjustable pin 36 which is located in 20 the path of movement of the crank 10, whereby when said crank is brought around in the direction opposite to that indicated by the arrow and carried in the position illustrated in Fig. 1, the pin 15 bends the 25 wire to form the eye of desired shape, as shown in Fig. 4.

When it is desired to impart a given angularity to the bent portion of the wire 23, I provide an additional gage 37 for indicating 30 such angularity, as shown in Fig. 1. This gage is formed by providing an extension of the frame as shown and marking thereon a series of lines coinciding with the radii of a circle having its center on the axis of the 35 arbor 12. It will therefore be seen that the end portion of a wire projecting beyond the arbor 12 and pin 15 may be bent around so as to coincide with one end of the radiating lines and the angularity desired thus imparted. As has been before noted, the two 40 screws 25 contained within the two lugs 24 provide adjustable stops for limiting the oscillatory movement of the member 26, which limitation is necessary for effecting 45 the bending operation, for the reason that at some time during such operation, the wire must be held against movement in a direction transverse with respect to its axis.

It will be apparent from the accompanying 50 drawing and the preceding description that I have provided a device of this character which is simple and efficient and by means of the varied adjustments shown and described is capable of readily lending itself to the making of a great number of accurate forms.

Having fully described my invention, what I claim and desire to secure by Letters Patent is:—

60 1. In a wire bending device, the combination of a main frame member; an oscillatory member provided with a groove for the reception of a wire; means for limiting the oscillation of said member; and a rotatory member provided with means for gripping

that portion of the wire extending from said groove.

2. In a wire bending device, the combination of a main frame member; an oscillatory member provided with means for the reception of wires of varying sizes, means for limiting the oscillation of said member; and a rotatory member provided with adjustable means for gripping that portion of the wire extending from said oscillatory member. 70 75

3. In a wire bending device, the combination of a main frame member; an oscillatory member provided with means for forming a groove of varying size for the reception of a wire; means for limiting the oscillation of said member; and a rotatory member provided with adjustable means for gripping that portion of the wire extending from said groove. 80

4. In a wire bending device, the combination of a main frame member; an oscillatory member adjustable longitudinally of said main frame member and provided with a groove for the reception of a wire; and a rotatory member located beyond the free end 90 of said oscillatory member and provided with means for gripping that portion of the wire extending from said groove. 85

5. In a wire bending device, the combination of a main frame member; an oscillatory member provided with a groove for the reception of a wire; adjustable means for limiting the oscillation of said member; and a rotatory member provided with means for gripping that portion of the wire extending 100 from said groove. 95

6. In a wire bending device, the combination of a main frame member formed with a circular depression and a bore coaxial therewith, a rotatory member having a cylindrical stem mounted in said bore and formed with an enlarged cylindrical portion mounted in said depression; a central pin projecting from said cylindrical portion; a second pin mounted adjacently to said central pin; a handle secured to said stem; and oscillatorily mounted guiding means on said frame which are adjustable for receiving wires of varying sizes. 110

7. In a wire bending device, the combination of a main frame member formed with a circular depression and a bore coaxial therewith; a rotatory member formed with an enlarged circular portion mounted in said depression, said rotatory member having a removable cylindrical stem mounted in said bore and one end thereof projecting from said cylindrical portion; a pin mounted upon said rotatory member adjacently to said projecting stem; a handle secured to 120 said stem and upon the end opposite that which projects from said enlarged cylindrical portion; and means for guiding the wire into juxtaposition to said projecting stem end and pin, said means being oscillatorily 125 130

mounted on said frame and adjustable in the longitudinal vertical plane containing the wire's axis.

8. In a wire bending device, the combination of a main frame member formed with a circular depression, and a bore coaxial therewith; a rotatory member having a cylindrical stem mounted in said bore and formed with an enlarged cylindrical portion mounted in said depression; a central pin projecting from said cylindrical member; an adjustable pin mounted adjacent to said central

pin; a handle secured to said stem and upon the end opposite that upon which said cylindrical member is secured; and oscillatory 15 means on said frame for guiding the wire, which means in conjunction with said frame are adapted to allow the wire to have a limited movement in a direction transverse with respect to its axis. 20

Signed by me, this 30th day of December, 1916.

MELVIN D. KILMER.
